Des. 99

Peter Low, Troy, New York.
Letters Patent (Design No. 99) dated 10th October 1846.

The schedule referred to in these Letters Patent and making part
of the same.

To all whom it may concern Be it known that I Peter Low
of the City of Troy County of Rensselaer and State of New York have
invented or produced a new Cooking Stone Pattern which stone is to be
called the New England Airtight Cooking Stone; and I do hereby de-
clare that the drawing or cut marked Fig. 1 accompanying this spe-
cification, and the stone now in the Patent Office sent as a model, are
a full and exact description of the same.

What I claim as new and desire to secure by Letters Patent
is the production of the new pattern above described.
